UNITED STATES PATENT OFFICE.

HERMANN KÖPPLINGER, OF VIENNA, AUSTRIA.

PROCESS FOR THE MANUFACTURE OF DOUBLE-GLAZED WINDOWS.

Application filed August 14, 1922. Serial No. 581,850.

To all whom it may concern:

Be it known that I, HERMANN KÖPPLINGER, a citizen of the Republic of Austria, residing at Vienna, Austria, have invented certain new and useful Improvements in a Process for the Manufacture of Double-Glazed Windows (for which application for patent was filed in Austria, February 10, 1921), of which the following is a specification.

10 The fact that double windows afford a sufficient protection from the loss of heat even when the distance between the panes is merely a few centimeters has led to the inner and outer panes being secured to one 15 and the same section, a single casement-sash window with double glazing thus being obtained. In spite of the great advantages which such windows possess on account of the simplicity of their manufacture, they have 20 not been used much, as the inner glass surfaces cannot be cleaned, and it appears impossible to insure an air tight joint between the two panes. It has therefore been necessary even in the case of double windows of 25 iron to arrange the outer and the inner panes in separate sash frames, in the same way as is usual in the case of wooden sash windows. But unlike the well known construction, one 30 of the two sash frames is not hinged to the window frame, but to the other sash frame, in order to enable both sash frames to be opened simultaneously. In double windows of this kind it appears desirable to keep the 35 distance between the panes as small as possible. The minimum dimension is however admissible only when the space between the panes can be closed in a perfectly air tight manner, that is to say when the two sash frames fit exactly into each other.

40 According to the present invention, this is rendered possible by a special process of manufacture which involves the division of the sash of a double-paned window along a plane lying between the two panes.

45 In order to enable of effecting this division by punching or shearing, the ends of the frame sides may be split before the sides are mounted to form the combined sash. The cutting of the latter into two sashes 50 may be carried out in such manner, that only one cut is made, for instance by means of a saw, or else by punching or shearing out a small strip of material from the stock.

This process of manufacturing ensures 55 perfect registry of the angles opposite each other at the corners; it guarantees exact reg-

istry of the two sash frames and produces sashes exactly fitting into each other even when the rolled stock used has not been straightened.

60 A construction of a double window made according to the invention is illustrated by way of example in the accompanying drawing.

Figure 1 is an elevation of the window, 65

Figure 2 a longitudinal section.

Figure 3 a cross-section, and

Figure 4 shows the rolled stock used for the manufacture of the two sash frames.

1 is the sash frame for the outer glazing, 70 and 2 the sash frame for the inner glazing. The outer sash frame 1 is connected by hinges 3 to the window frame 6, and by hinges 4 to the inner sash frame. The stock used for the inner sash frame agrees substantially 75 with the usual frame cross-section. The outer sash frame has an outwardly turned gutter-like extension 5 in which is mounted the inner edge of the outer frame. The gutter or channel 5 is filled with cement 80 or the like in order to avoid leaky places liable to be formed owing to any unevenness of the rolled stocks.

The window consisting of the inner and outer sash is mounted in the outer frame 6 85 with a "double butt". One butt is formed by the flange 7 of the outer sash frame and the outer flange 8 of the frame 6, and the other by the flange 10 of the sash frame 2 and the inner flange 9 of the frame 6. Si- 90 multaneous action of the two butts presupposes that the distance between the two flanges 8 and 9 is in fact identical at all points and agrees exactly with the distance 95 between the two flanges 7, 10 of the outer and inner sash frames.

Such an accuracy cannot however be obtained in the present state of the rolling industry. This drawback is overcome according to the invention by making the distance between the two flanges 8, 9 of the outer frame greater than the distance between the flanges 7, 10, and by making one of the two flanges (for instance the flange 9) of such a small thickness that it can be bent 105 by hand or hammered down and easily brought into contact with the adjoining flange 10 of the sash frame. In order to avoid the necessity of rolling undercut sections, the flange 9 to be bent should be pref- 110 erably arranged in the same plane as the flange 11, as shown dotted in Figure 3 of the

drawing. The window frame 6 is provided at the inner side with a groove 12 with which engages the flange 10 of the lateral part of the sash frame 2, adjacent the hinge 3, for the purpose of improving the joint between the two sash frames and the frame 6, and of making impossible any unauthorized removal of the windows by removing the hinges 3.

- 10 The part above the line *a—a* is identical with the cross-section of the inner sash and the part below the line *b—b* with that of the outer sash. These parts are united by the stripe of material between the lines *a—a* and *b—b*. From the metal bars having this cross-section pieces of the length of the sash-sides are cut and then mounted to form a frame. If now the stripe between the lines *a—a* and *b—b* is cut out, for instance by 15 means of a saw, the resulting two frames will exactly fit into one another. Separating these two frames by punching or shearing would require a rather complicated machinery, but the latter can be dispensed with, 20 if the end parts of said stripes of each side-piece are cut out before the frame is mounted. Consequently, after mounting, only the middle part of the stripe is to be cut out, which operation can easily be effected by 25 means of simple known punching or shearing machines.

What I claim is:

1. A process for the manufacture of double glazed windows with hinged outer

and inner sashes, which process consists in 35 preparing rolled fashioned metal bars, the cross-section of which represents the united cross-sections of the two sash frames placed side by side with a small strip connecting said two cross-sections, forming from these 40 bars a frame of the dimensions of the sashes to be made and thereupon cutting through this frame at the joint of the two sash cross-sections.

2. A process for the manufacture of 45 double glazed windows with hinged outer and inner sashes, which process consists in preparing rolled fashioned metal bars, the cross-section of which represents the united cross-sections of the two sash-frames placed 50 side by side with a small strip connecting said two cross-sections, forming from these bars frame sides, partly separating the two cross-sections at the ends of each frame side, then uniting the sides to form a frame of the 55 dimensions of the sashes to be made and thereupon cutting through the remaining joint of the two sash cross sections.

3. A method for manufacturing double glazed windows as set forth in claim 1, in 60 which method close fitting of the sashes to the outer frame of the window is obtained by bending a thin flange provided on the outer frame of the window so as to touch closely the sash frame.

In testimony whereof I have affixed my signature.

HERMANN KÖPPLINGER.
